APPARATUS FOR CUTTING SHEET MATERIAL

Albert C. Perbal, St. Louis, Mo., assignor of one-half to Lawrence H. Cohn, St. Louis, Mo.

Application January 20, 1939, Serial No. 251,870

18 Claims. (Cl. 164—60)

This invention relates to apparatus for cutting sheet material into narrow strips or ribbons and more particularly to improvements in stripping apparatus of the type that employ two coacting 5 sets of shearing discs mounted on parallel drive shafts.

The invention resides in the novel manner in which the shearing discs are mounted on their respective shafts, the discs being loosely retained 10 on the shafts to provide for equalization of contact pressures and yet which, by reason of the manner in which they are mounted, maintain themselves in proper operating position without requiring additional agencies for this purpose 15 that tend to restrict their freedom of adjusting movement on the shafts.

In certain early forms of disc type stripping machines the shearing discs were rigidly secured to the shafts. Because of the difficulty of 20 adjusting and equalizing the contact pressures between coacting discs, and of maintaining such pressures uniform throughout the series thereof, the rigid or fixedly mounted discs were found to be impractical. Such apparatus was superseded 25 by a somewhat improved construction wherein the cutting discs, in the form of annular washers, are yieldingly mounted on their shafts, a rubber sleeve, or rubber spacers disposed between the discs being employed to maintain them in proper 30 operating position. This method has likewise failed to provide a practical solution to the problem because it does not eliminate the tendency of the discs to assume angular positions and to 35 creep along the shafts, a tendency that has the effect of rendering non-uniform the contact pressures between the sets of coacting discs.

This undesirable tendency is believed to be inherent in the discs because of the character 40 of their mounting which gives rise to a condition of unstable equilibrium. Thus, when a relatively thin annular washer is loosely disposed on a rotating rod or shaft the washer will begin to revolve in a plane normal to the shaft. However, any slight displacement of the washer from the 45 normal plane causes forces to be set up which tend to draw the washer into the plane of the shaft, and the washer then tends to creep or travel along the shaft. A well known example 50 of this phenomenon is found in machine shops wherein horizontal power shafts are maintained clean and bright by the simple expedient of a washer loosely disposed thereon, the washer automatically traveling back and forth along the shaft. In the examples referred to it will be

5 noted that the shaft contacts the inner peripheral edge of the washer.

However, when a thin disc or washer is rotat- 10 ingly supported at its outer peripheral edge, as may be accomplished by placing the disc on edge 5 on the inner surface of a hollow rotating body, such as a tube, the disc will be maintained in a condition of stable equilibrium while it re- 15 volves, and forces tending to upset the disc will be opposed by other natural forces that tend to 10 maintain the disc in a plane normal to its axis of rotation. Moreover, there is no tendency of the disc to travel laterally as in the case of the annular washer loosely disposed on a revolving shaft.

An object of my invention is attained by applying 15 the above mentioned phenomenon to the cutting discs of a stripping machine wherein the discs are floatingly mounted and self-adjustable on their shafts, yet exhibit no undesirable tendency to tilt or creep laterally. 20

The advantages of my improved stripping ap- 25 paratus are that the contact pressure between the coacting discs is uniform with respect to all coacting pairs thereof and the contact pressure may be readily adjusted to adapt the apparatus 30 to various kinds of sheet material; sheet material such as Cellophane and very thin metal which heretofore was found difficult to cut smoothly and evenly by apparatus of this general type is readily and satisfactorily acted upon by the ap- 35 paratus of my invention. Resharpening of the discs is seldom necessary.

Other objects and advantages will appear from 35 the following description and accompanying draw- 40 ing which illustrate an operative embodiment of my invention.

In the drawing, Fig. 1 is a front elevation of a 45 cutting machine embodying the features of my invention; Fig. 2 is an enlarged detailed sectional view taken in the plane of the axes of the shafts; Fig. 3 is a transverse sectional view taken on line 40 3—3 of Fig. 2, and Fig. 4 is a sectional view showing fragmentary portions of a cutting disc and retainer members in separated relation.

Referring now by characters of reference to the 45 drawing, 10 and 11 designate, respectively, upper and lower parallel shafts upon which the cutting discs are mounted. These shafts are journaled in suitable bearing blocks 13 and 14 carried by spaced supports 15 which form rigid extensions 50 of a base plate 16. A pair of gears 17 and 18, fixed to the projecting ends of shafts 10 and 11, are engaged with each other to cause the shafts to revolve in unison under the influence of suit- 55 able driving means (not shown).

Loosely mounted on each of the shafts 10 and 11 in a manner and by means hereinafter described are a plurality of cutters or slitters in the form of annular discs 19 which, in the present example, are of thickness equal to the width of the strips to be cut thereby. The discs on one shaft are arranged in intercalated shearing relation with respect to the discs of the other shaft, each disc with the exception of the end discs cooperating with and being disposed between two adjacent discs on the opposite shaft. Since the two sets of discs and the means by which they are retained on their respective shafts may be and preferably are alike in all material respects descriptive reference will be made to only one of the disc assemblies.

Mounted on the shaft 10 are a plurality of annular spacer members 20, hereinafter also referred to as disc retainers. The members 20 preferably comprise collar portions 21 (Fig. 4) which are disposed in end abutting relation and which fit closely upon the shaft, the members 20 being held against turning relative to the shaft by means of keys 22 seated in complementary keyways formed in the shaft and collar portions. The members 20 are confined between end members 23 and the assembly is tightly held together and against endwise displacement on the shaft by collars or locking nuts 24 threaded on the shaft.

The members 20 and 23 are preferably formed with annular flange portions 25 (Fig. 4) that extend radially from the collar portions 21, the flange portions 25 being of reduced thickness as compared to the thickness or axial dimension of collar portions 21. Formed at the outer peripheral margin of flange portion 25 is an annular rim portion 26, also of lesser thickness or axial dimension than that of the collar portion 21, the rim 26 forming laterally projecting flanges 27.

As best appears from Figs. 2 and 4, the retainer members 20 coact to define a series of uniformly spaced annular grooves or channels 28 which terminate inwardly in annular spaces 29 of enlarged width as compared to the width of the channels 28. Otherwise stated, the channels 28 are undercut to form the spaces 29, the said channels serving to receive the inner peripheral portions of the cutting discs 19 and loosely to position the same.

The cutting discs 19 have annular grooves 30 formed in their opposite side surfaces that define relatively thin annular neck portions 31 which fit loosely within the channels 28, the neck portions 31 terminating inwardly in annular rim portions 32 that produce the laterally projecting flanges 33, the rim portions 32 fitting loosely in the channel spaces 29. The diameter of the openings 34 in the cutting discs is appreciably greater than the outer diameter of collar portions 21, and likewise, the internal diameter of the flanges 27 is appreciably greater than the outer diameter of disc flanges 33, whereby the discs are translatable to a limited degree radially with respect to the retainer members 20. Of importance however, is the fact that the difference between the inner diameter of the flange 27 and the outer diameter of disc flange 33 is less than the difference between the diameter of the disc opening 34 and the outer diameter of collar portion 21. When the aforesaid relative dimensions are adhered to, rolling contact of the cutting disc will occur at the inner surface of flange 27 and not at the outer surface of collar portion 21. This provision and result is illustrated in Figs. 2 and 3 where it will

appear that the rim portions 32 of the cutting discs contact the inner surfaces of the rim portions 26 of the retainer members at a point indicated at 35, while at the side of the shaft diametrically opposite such point a space 36 occurs between the outer collar surface and the inner peripheral margin of the cutting disc.

Thus, it will appear that the members 20 form a cage-like structure in which the inner peripheral portions of the cutting discs are loosely retained, and the discs are adapted for rolling contact on races that face toward the axis of rotation, formed on inner surfaces of the aforesaid cage structure. Since the cutting discs are translatable to a limited degree both laterally and edge-wise with respect to the shaft and to their retainer members, they may be said to be floatingly mounted.

As a means for maintaining the discs in proper shearing relation it is desirable to provide a pair of bearing members 37 which coact to force the inter-engaging portions of the discs together. The bearing members or shoes 37 preferably are in the form of small rollers 38 which are journaled on rods 39 disposed to slide longitudinally in suitable guide openings in the supports 15. The rollers 38 bear laterally against, and roll upon the outer faces of the end cutting discs, being arranged to contact such discs in the zone of the overlapping portions thereof. Springs 40 on rods 39 act upon the rollers 38 and provide the forces for holding the overlapping portions of the discs in lateral, shearing engagement with each other. Suitable means (not shown) are preferably provided for rendering the pressure of springs 40, and hence disc contact pressures, adjustable, so that the disc contact pressures may be varied to adapt the apparatus to cut sheet material of different kind and thickness.

In operation, the material to be cut, indicated at 41, is fed into and through the interengaging shearing margins of the discs as shown in Fig. 3. The material 41 tends to force the two sets of loosely mounted discs away from each other and into frictional contact with the inner race surfaces of their rotating retainer members as hereinabove explained, the cutting discs deriving their rotational forces through frictional contact with the retainer members.

It is desired to point out that in the disc mounting arrangement described herein, the discs bear upon their associated retainer races at the outboard sides of the shafts (note the location of contact points 35, Fig. 2), and they contact the discs with which they coact at the inboard sides of the shafts. Thus it will appear that the major contact zones of each disc are relatively widely spaced and occur at relatively opposite sides of the shaft upon which the disc is mounted. This factor, it is believed, has great stabilizing effect on the loosely mounted discs.

While I have described my invention with reference to a machine for cutting sheet material into strips and which employs a multiplicity of cutting discs, the invention resides principally in the method and means by which a cutting disc is loosely mounted in a stabilized manner on a shaft or other rotating body. Obviously the means of the invention may be incorporated in cutting apparatus employing but two coacting discs for producing a single shear cut in sheet material, or in a machine employing but a single cutting disc which is adapted to operate in edge-abutting relation to a backing roll.

It will also appear that various changes and

modifications may be made in the apparatus herein shown and described without departing from the spirit and full intended scope of my invention as defined by the appended claims.

5. I claim:

1. In a machine for cutting sheet material, a rotatable shaft, an annular cutting disc loosely disposed on said shaft, and a disc-retaining member fixed to the shaft, adapted to impart shaft rotation to the disc, said member having a cage portion in loose, environing relation to an inner peripheral portion of said disc.

10. In a machine for cutting sheet material, a rotatable shaft, an annular cage fixed to said shaft, and a cutting disc loosely retained on said shaft by said cage, said cutting disc being formed with a bearing portion loosely journalled within said cage.

15. In a machine for cutting sheet material, a circular cutting disc having means integral therewith forming a bearing portion, and a rotatable member on which said disc is mounted, said member having an annular journal-forming portion surrounding and loosely confining the bearing portion of said cutting disc.

20. In a machine for cutting sheet material, a rotatable member having an annular flange formed thereon, and a cutting disc having a cylindrical bearing portion disposed within and bearing on the inner surface of said flange, the inner diameter of said flange being appreciably greater than the diameter of the bearing portion of said disc.

25. In a machine for cutting sheet material, a rotatable shaft, an annular cutting disc loosely disposed about said shaft, said disc having an annular, laterally projecting flange thereon, an annular retaining member fixed to said shaft, said retaining member having a laterally projecting flange surrounding said disc flange, said retainer being adapted to hold said disc out of contact with the shaft, yet permitting translational movement of the disc relative thereto.

30. In a machine for cutting sheet material, a rotatable shaft, an annular cutting tool disposed about said shaft, the internal diameter of said tool being substantially greater than the diameter of said shaft, said tool having an annular, laterally projecting flange thereon, a member fixed to said shaft, said member having an annular portion surrounding said tool flange and forming a race upon which the tool flange is adapted to roll.

35. In a machine for cutting sheet material, a rotatable shaft, a collar fixedly secured to the shaft for rotation therewith, said collar having an annular undercut channel formed therein, an annular cutting disc loosely mounted on said collar with its inner peripheral margin disposed within said channel, said disc having a lateral flange thereon fitting loosely within the undercut portion of said channel.

40. In a machine for cutting sheet material, a rotatable shaft, an annular cutting disc on said shaft, the internal diameter of said disc being substantially greater than the diameter of said shaft, and a disc-retaining member adapted to impart shaft rotation to the disc, said member having a cage portion fixed to said shaft disposed in loose, environing relation with an inner peripheral portion of the disc.

45. In a machine for cutting sheet material, a rotatable shaft, an annular cutting disc on said shaft, the internal diameter of said disc being substantially greater than the diameter of said

shaft, and a disc-retaining member on the shaft adapted to impart shaft rotation to the disc, said retaining member having an annular cage-forming portion in loose, confining relation to an inner peripheral portion of said disc, said retaining member being adapted to prevent contact between said disc and shaft.

5. In a machine for cutting sheet material, a rotatable shaft, an annular cutting disc on said shaft, the internal diameter of said disc being substantially greater than the diameter of said shaft, and a disc-retaining member fixed to the shaft and including a substantially annular cage-forming portion, said disc having an inner peripheral portion floatingly confined within the cage-forming portion of said retaining member, said retaining member preventing contact between said disc and shaft.

10. In a machine for cutting sheet material, a rotatable shaft, a collar fixed for rotation with said shaft and having an annular laterally projecting flange providing a race or bearing surface that faces toward the center of rotation, an annular cutting disc floatingly retained on said shaft by said collar, said disc having an annular shoulder formed thereon, said shoulder being disposed within said flange and adapted for rolling contact with said bearing surface.

15. Apparatus for cutting sheet material comprising a rotatable shaft, a plurality of annular cutting discs floatingly mounted on said shaft, a plurality of annular disc-retaining members fixed on the shaft for rotation therewith, said members being disposed between said discs and coacting to form annular, undercut channels adapted loosely to receive the discs, said discs having lateral flanges formed on their inner peripheries that extend into the undercut portions of said channels, the outer surfaces of said flanges being adapted for rolling contact on said members; a second set of cutting discs loosely mounted in the aforesaid manner on a rotatable shaft extending parallel to the first said shaft, the discs of the respective shafts being disposed in intercalated laterally contacting relation.

20. Apparatus for shearing sheet material comprising a rotatable shaft, a plurality of annular cutting discs floatingly carried by said shaft, the internal diameter of said discs being substantially greater than the diameter of the shaft, a plurality of disc-retaining members fixed for rotation with the shaft, each disposed between an adjacent pair of cutting discs, said discs having flanges projecting laterally at the inner periphery thereof, said retaining members having lateral flanges disposed in overlapping relation to, and adapted to be engaged by said disc flange, said discs being rotatable and translatable relative to said retaining members, and means providing a plurality of shearing surfaces respectively co-acting with said cutting discs.

25. An apparatus for cutting sheet material comprising a rotatable shaft, a plurality of collars carried by and disposed in end-abutting relation on said shaft, means securing said collars together and to the shaft for rotation therewith, each of said collars having an annular, radially projecting flange formed thereon, said collar flanges being axially spaced with respect to each other; a plurality of annular cutting discs loosely disposed on said collars, each between a pair of adjacent collar flanges, said discs having annular laterally projecting flanges thereon, said collar flanges having annular portions surrounding the disc flanges and providing a race upon which the

discs are adapted to bear, said discs being floatingly supported by said collars.

15. Apparatus for shearing sheet material comprising a rotatable shaft, a plurality of annular cutting discs disposed on said shaft, the inner diameter of each of said discs being substantially greater than the diameter of said shaft, means floatingly retaining the discs on the shaft comprising a plurality of collars fixed to the shaft, each disposed between a pair of adjacent cutting discs, each of said collars having an internal annular race or bearing surface formed thereon, each of said discs having a cylindrical bearing portion loosely confined within and adapted to bear radially outwardly upon the race of an adjacent collar, and means providing a plurality of shearing edges, each of said shearing edges coacting with one of said cutting discs.
16. In a machine for cutting strip material, a pair of parallel rotatable shafts, each of said shafts having an annular cutting disc disposed thereon, and a collar fixed to the shaft adapted loosely to retain said cutting disc, said collar having an annular flange providing an internal bearing race for said disc, said disc having an annular bearing portion surrounded by and adapted to roll upon said race, the discs on the respec-

tive shafts being disposed in overlapping engagement and coacting to shear material fed thereto.

17. A machine for cutting sheet material into strips, a pair of parallel, rotatable shafts, a plurality of cutting discs loosely disposed on said shafts with the discs of one shaft extending between and adapted to coact laterally with the discs of the other shaft, a plurality of annular spacer members on the shafts, each disposed between a pair of adjacent cutting discs, said cutting discs having annular, laterally projecting flanges formed near the inner periphery thereof, said spacer members having annular, laterally projecting flanges formed near the outer periphery thereof, and disposed in overlapping relation with said disc flanges, said spacer flanges providing an internal race upon which the discs are adapted to roll, and means at the opposite ends of the disc assembly tending axially to compress the assembled discs.

18. A machine for cutting sheet material into strips as set forth in claim 17 wherein the compression means at the opposite ends of the disc assembly comprise resiliently mounted shoes disposed in bearing engagement with the end discs of the assembly, in registry with the interengaging portions of the coacting discs.

ALBERT C. PERBAL.
